TACK-FREE ALKARYL SULFONATE
DETERGENTVincent J. Keenan, Ardmore, Pa., assignor to The
Atlantic Refining Company, Philadelphia, Pa.,
a corporation of PennsylvaniaNo Drawing. Application June 17, 1950,
Serial No. 168,833

12 Claims. (Cl. 252—161)

1

This invention relates to a detergent composition containing a water-soluble alkyl-substituted aryl sulfonate, and more particularly to a composition containing a water-soluble alkyl-substituted aryl sulfonate which does not develop objectionable tacky, adhesive sensations when used in contact with the human skin.

Detergent compositions in the form of bars, creams, shampoos, and similar cosmetic products have been made heretofore in which water-soluble alkyl-substituted aryl sulfonates constituted the surface active agent. Since these sulfonates, which hereinafter will be termed "alkyl aryl sulfonates," do not form insoluble compounds with the calcium or magnesium ions found in hard water, it was assumed that such compositions would prove especially valuable in hard water areas where present fatty acid soap compositions precipitate insoluble soaps and exhibit poor detergent and lather properties. Cosmetic preparations containing an alkyl aryl sulfonate were found, however, to produce an adhesive or tacky sensation on the skin. This property is objectionable, so much so, that in spite of the superior detergency, lather, and solubility properties of alkyl aryl sulfonate compositions as compared with fatty acid soap compositions in hard water, the sulfonate compositions have not met with public acceptance in the cosmetic field.

The exact reason for the development of this tackiness by alkyl aryl sulfonate-containing compositions has not been exactly determined. However, the alkyl aryl sulfonates are highly active surface-active agents and consequently, it is possible that they remove most of the natural protective oils of the skin, with the result their strongly polar sulfonate radicals become attached to or at least closely associated with the proteins of the skin, and thereby produce the characteristic, highly objectionable tacky sensation. Whatever the theoretical explanation, this "tack" has prevented full commercial utilization of alkyl aryl sulfonates in cosmetic detergents and until the present invention, no 45 solution had been found to this problem.

In addition, alkyl aryl sulfonate formulations are extremely difficult to extrude into bar forms. These formulations are much too hard and either "freeze" in the extruder or discharge as lumps instead of in the form of a smooth, coherent, gel-like ribbon.

It is an object of this invention to produce a detergent composition in the form of a solid bar, cream, or liquid which contains an alkyl aryl sulfonate as surface active agent, and which, when used in contact with the human skin, does not develop objectionable tacky sensations.

2

It is an additional object to provide a detergent composition containing an alkyl substituted aryl sulfonate which may be easily and smoothly extruded into coherent gel-like ribbons for the production of bars.

The detergent compositions of the present invention may be prepared by forming a primary aqueous dispersion of the alkyl aryl sulfonate together with commercial lecithin in an amount of at least 20%, but less than 70% by weight, based on the weight of the dry sulfonate. The amount of water used to form the primary dispersion is not critical, but in general may range, for example, between 0.5 and 5 volumes of water per volume of dry ingredients, this range being preferred in order to form a fluid dispersion which does not contain a large excess of water, since the water must be removed by a subsequent drying operation. In order to improve the appearance or performance of the finished product, various agents such as fillers, abrasives, dyes, perfumes, emollient oils, glycerol, and waxes may be dispersed in the primary mixture to form a final dispersion which when drum or spray dried, will produce a product in the form of freely-flowing flakes, sheets, pellets, or beads. In addition, such dried material may be molded into smooth bars or plodded or milled and subsequently extruded, sliced, and molded into bars.

30 The compositions produced as above described, in addition to their ease of extrusion to form bars, are entirely free of the objection of causing a tacky sensation when used in contact with the human skin.

35 It is known that in many cases, fatty acid soap products cause severe dermatic and allergic reactions due to the fact that they hydrolyze in water to give an alkaline solution. The compositions of the present invention, however, entirely avoid such objectionable reactions since both the lecithin and alkyl aryl sulfonates are non-alkaline even in aqueous solutions.

The water-soluble alkyl aryl sulfonates suitable for use in the present detergent compositions are prepared by sulfonating a suitable alkyl aromatic and neutralizing the resultant alkyl aryl sulfonic acid with an alkaline compound.

50 The alkyl aromatics suitable for preparing the desired sulfonates have an alkyl group containing from 8 to 15 carbon atoms. In addition to the long chain alkyl group, short chain alkyl groups may be substituted for other nuclear hydrogen atoms of the aromatic. These compounds may be prepared by a variety of methods, for example, by the alkylation of an aromatic hydrocarbon with a branched-chain olefin having from 8 to 15 carbon atoms in the presence of a catalyst such as $AlCl_3$, HF , H_2SO_4 , BF_3 , or

similar acid-type catalysts. The olefins may be obtained from the polymerization of propylene over phosphoric acid or similar catalyst or by the polymerization of butylenes, etc. The aromatic employed may be benzene, naphthalene, toluene, any one of the isomeric xylenes or mixtures of such isomers, ethyl benzene, propyl benzene, or similar lower alkyl aromatics.

Another method of preparation involves the reaction of an alcohol containing from 8 to 15 carbon atoms with an aromatic hydrocarbon in the presence of such catalysts as H_2SO_4 , BF_3 , $BF_3-H_2SO_4$, $BF_3-H_3PO_4$, or $AlCl_3$. The alcohols may be obtained by the reaction of an olefin with carbon monoxide and hydrogen in the so-called "Oxo" process, or by the oxidation of paraffinic hydrocarbons. The aromatic hydrocarbon may be benzene, naphthalene, toluene, any one or a mixture of the isomeric xylenes, ethyl benzene, propyl benzene, or similar lower alkyl aromatics.

A third method of preparation of the alkyl aromatics employs a chlorinated hydrocarbon having from 8 to 15 carbon atoms reacted with the aromatic hydrocarbon in the presence of a Friedel-Crafts catalyst such as $AlCl_3$. The alkyl halide may be conveniently obtained by chlorinating the proper petroleum fraction such as a kerosene fraction. The aromatics suitable in the previous examples are likewise suitable in this method.

Typical compounds which fall within this class are nonyl benzene, dodecyl benzene, pentadecyl benzene, nonyl toluene, dodecyl toluene, pentadecyl toluene, dodecyl xylene, and the like. Obviously, a large number of similar compounds might be enumerated; however, in the interest of brevity and clarity, it is sufficient to state that all such compounds having an aromatic nucleus with one side-chain containing from 8 to 15 carbon atoms and including also those compounds wherein the aromatic nucleus has, in addition to the 8 to 15 carbon atom side-chain, one or more short-chain alkyl radicals up to 3 carbon atoms in length.

The agents which may be employed in sulfonating the alkyl aromatics to produce the alkyl aryl sulfonic acid include sulfuric acid ranging in concentration from about 98% to 100%, fuming sulfuric acid containing up to 30% free SO_3 , chlorosulfonic acid, and similar reagents.

The alkyl aryl sulfonic acid resulting from the sulfonation step may be neutralized with a variety of alkaline compounds, for example, with an alkali or alkaline earth metal hydroxide or carbonate, with ammonia, or with various amines including primary, secondary, and tertiary alkyl amines, alkyl alkanol amines, alkanol amines, heterocyclic amines, or other alkaline compounds which will produce water-soluble sulfonates. Specific examples of the amines include methyl amine, dimethylamine, trimethylamine, ethanolamine, diethanolamine, diethyl ethanolamine, ethyl diethanolamine, triethanolamine, pyridine, methyl pyridine, and similar compounds.

The water-soluble alkyl aryl sulfonate soap resulting from the neutralization step may be used in the final composition either alone or in combination with various amounts of a similar soap or soaps prepared as above described.

The lecithins which may be used include both the animal and vegetable types, all of which are structurally, esters of glycerol and resemble a fat, but differ therefrom in that at least one fatty acid radical is replaced by a complex amine-phos-

phoric acid radical. The amine is a quaternary ammonium compound known as choline. The lecithins of the vegetable type are derived from soy bean, corn, linseed, peanut, or other similar oils and are commercially available as dispersions or solutions in from 30% to 40% of the oils. The term "lecithin," as used herein and in the appended claims, refers to the commercial product, which as stated, contains approximately 65% of the lecithin and 35% of the oil. Soya lecithin is especially useful from the standpoint of availability and low cost.

The amount of lecithin employed varies with the intended use of the final detergent. However, in general, the amount ranges between 20% to 70% by weight based on the dry sulfonate. Amounts less than 20% fail to impart detackifying properties to the finished detergent, whereas amounts greater than 70% interfere with the detergent and lathering properties of the finished product. It has been found, in fact, that the addition of lecithin to alkyl aryl sulfonate compositions fails to improve detergent action, lathering, or foam stability of the finished detergent. The only effect of the lecithin, as has been stated, is to improve the extrudability and eliminate "tack." The amount of sulfonate and lecithin in the finished detergent preferably ranges between 5% and 65%, and 1% to 40%, respectively. However, in all cases, including those intermediate the above limits, the amount of the lecithin by weight based upon the weight of sulfonate must range between 20% and 70%. The remainder of the composition may consist of fillers, dyes, perfumes, emollient oils, and waxes, all of which are inert with respect to detergent action. Small amounts of short-chain sodium alkyl aryl sulfonates such as sodium xylene sulfonate, sodium isopropyl sulfonate, sodium isopropenyl sulfonate, and the like, may be added to the composition for the purpose of producing rapid sudsing of the finished detergent, but this refinement is not necessary or critical.

As hereinbefore stated, the instant compositions are suitable for both solid and liquid formulations. In the two tables immediately following, typical formulations are shown giving desirable percentages of components, on the basis of the weight of the finished composition for a bar soap (Table I) and a liquid soap (Table II). These examples are not to be construed as limiting the invention, since, as is well known in the art of soap manufacture, many modifications may be made by the addition of various inert materials, some of which have been enumerated hereinbefore.

TABLE I

Bar soaps

	Per cent
Alkyl aryl sulfonate	15 to 50
Lecithin ¹	3 to 25
Starch	0 to 50
China clay	0 to 35
Talc	0 to 35
Xylene sulfonate	0 to 20
Polyethylene glycol waxes (2000-6000 mol. wt.)	0 to 10
Natural waxes (carnauba, candellila, bees, etc.)	0 to 10
Saponin	0 to 5

¹ In all cases, the amount of lecithin ranges between 20% and 70% of the alkyl aryl sulfonate on dry weight basis.

5
TABLE II
Liquid soaps

	Per cent
Alkyl aryl sulfonate (particularly the triethanolamine salt) ¹	20 to 65
Lecithin	5 to 13
Water	75 to 22

¹ The upper limit given is true only for alkyl aryl sulfonates which are soluble to the extent, for example, the triethanolamine sulfonates; other sulfonates such as alkali metal sulfonates are soluble in water in an amount only up to about 30% by weight, which obviously would define the upper limit in those cases.

In the case of the liquid soaps, as in all others, the weight of lecithin ranges between 20% to 70% by weight of the sulfonate. Where the sulfonate is present in amounts near the upper range of concentration it may be impossible to have the lecithin present in amounts approaching 70% because of solubility limitations. Where, however, the amount of sulfonate is somewhat removed from the upper range, the amount of lecithin may be increased accordingly. By way of example, a composition might contain 40% sulfonate, 28% lecithin, and 32% water. Compositions having amounts of sulfonate and lecithin near the upper limits of the above stated ranges for liquid soaps, may actually be cream or gel-like in form suitable for shampoos, whereas compositions containing amounts of sulfonate and lecithin nearer the lower limits will be true liquids suitable for hand cleansers and similar uses. It should also be noted that at least a part of the water may be replaced by a lower aliphatic alcohol such as ethyl alcohol, isopropyl alcohol, etc., a substitution heretofore known and practiced for the purpose of giving an astringent property to the soap.

In Table III, several practical formulations for bar soaps are given to further illustrate the invention.

TABLE III

Component	Composition (amounts in parts by weight)											
	1	2	3	4	5	6	7	8	9	10	11	12
sodium dodecyl benzene sulfonate	100	100	150	100	50	25	25	25	25	25	130	
sodium nonyl benzene sulfonate						75						
magnesium dodecyl benzene sulfonate						150	75			25		
triethanol amine salt of dodecyl benzene sulfonic acid												
soya lecithin	50	70	50	50	30	40	50	50	50	50	50	55
corn lecithin										30		
linseed oil lecithin												
starch	150	90	80	200	100	50	50	50	150	75	125	60
talc	25	10					60	20	25	50		50
xylene sulfonate	75	20	5		25	20	25	25	50	35	50	25
polyethylene glycol wax (mol wt. about 6000)	30		10	30	15	10			15	10	15	
carnauba wax	25	10	10	20	10	5		10	5	10		
beeswax									10			
saponin	5	5	5	5	8	10	5	5	5	5		

In all of the above examples, the active detergent component of such formulations is shown as an alkyl aryl sulfonate or mixture of alkyl aryl sulfonates, however, if desired, a portion of the alkyl aryl sulfonate or sulfonates may be replaced with other known detergents such as alkyl sulfates, alkyl aryl sulfates, fatty acid soaps and similar compounds.

I claim:

1. A detergent composition comprising a water-soluble salt of an alkyl aryl sulfonic acid and from 20% to 70% of lecithin by weight based on

the weight of the dry salt of the alkyl aryl sulfonic acid.

2. A detergent composition comprising a water-soluble salt of an alkyl aryl sulfonic acid in which the alkyl radical contains from 8 to 15 carbon atoms and from 20% to 70% of lecithin by weight based on the weight of the dry salt of the alkyl aryl sulfonic acid.

3. A detergent composition comprising the sodium salt of an alkyl aryl sulfonic acid in which the alkyl radical contains from 8 to 15 carbon atoms, and from 20% to 70% of lecithin by weight based on the weight of the dry salt.

4. A detergent composition comprising the triethanol amine salt of an alkyl aryl sulfonic acid in which the alkyl radical contains from 8 to 15 carbon atoms, and from 20% to 70% of lecithin by weight based on the weight of the dry salt.

5. A detergent composition comprising the sodium salt of nonyl benzene sulfonic acid and from 20% to 70% of lecithin by weight based on the weight of the dry salt.

6. A detergent composition comprising the sodium salt of dodecyl benzene sulfonic acid and from 20% to 70% of lecithin by weight based on the weight of the dry salt.

7. A detergent composition comprising the sodium salt of pentadecyl benzene sulfonic acid and from 20% to 70% of lecithin by weight based on the weight of the dry salt.

8. A detergent composition comprising the magnesium salt of dodecyl benzene sulfonic acid and from 20% to 70% of lecithin by weight based on the weight of the dry salt.

9. A detergent composition comprising a water-soluble salt of an alkyl aryl sulfonic acid in an amount ranging between 15% and 65% of the total weight of the detergent and lecithin in an amount ranging between 20% and 70% by weight based on the weight of the dry salt of the alkyl aryl sulfonic acid.

10. A detergent composition comprising a water-soluble salt of an alkyl aryl sulfonic acid in which the alkyl radical contains from 8 to 15 carbon atoms, said salt of the sulfonic acid being present in an amount ranging between 15% and 65% of the total weight of the detergent, and lecithin in an amount ranging between 20% and 70% by weight based on the weight of the dry salt of the sulfonic acid.

11. A detergent composition comprising the sodium salt of an alkyl aryl sulfonic acid in which the alkyl radical contains from 8 to 15 carbon

atoms, said salt being present in an amount ranging between 15% and 65% of the total weight of the detergent, and lecithin in an amount ranging between 20% and 70% by weight based on the weight of the dry salt.

12. A detergent composition comprising the triethanolamine salt of an alkyl aryl sulfonic acid in which the alkyl radical contains from 8 to 15 carbon atoms, said salt being present in an amount ranging between 15% and 65% of the total weight of the detergent, and lecithin in an amount ranging between 20% and 70% by weight based on the weight of the dry salt.
